UNITED STATES PATENT OFFICE.

CHARLES A. SCHMITT, OF KANSAS CITY, MISSOURI.

LINK-MOTION FOR LUBRICATORS, &c.

SPECIFICATION forming part of Letters Patent No. 434,839, dated August 19, 1890.

Application filed March 21, 1890. Serial No. 344,768. (No model.)

To all whom it may concern:

Be it known that I, CHARLES A. SCHMITT, of Kansas City, in the county of Jackson and State of Missouri, have invented certain new and useful Improvements in Link-Motions for Lubricators, &c., of which the following is a full, clear, and exact description, reference being had to the accompanying drawings, forming a part of this specification.

- 10 My invention relates to a link-motion which may be used in connection with lubricators and various other devices; and my invention consists in features of novelty hereinafter described, and pointed out in the claims.
- 15 Figure I is a side elevation of my improved device, showing the same attached to a lubricator used in connection with an elevator. Fig. II is an enlarged detail perspective of the link. Fig. III is an enlarged detail perspective of the link-operating pulley with trip-arms attached.

- 20 Referring to the drawings, 1 represents an ordinary elevator which works vertically in the frame 2.
- 25 3 represents the cable by which the elevator is raised or lowered, said cable being attached at 4 to the elevator, thence passing over a pulley 5, thence around a pulley 6, and thence around a pulley 7, journaled at 8 to
- 30 the upper end of the operating piston-rod 9. The piston-rod 9 is operated by the usual hydraulic cylinder 10.

- 35 11 represents an oil-cylinder suitably secured to a fixed point, as shown at 12.
- 40 13 represents an observation-glass cylinder having connection with the lower end of the oil-cylinder 11, said observation-cylinder having a drain-cock 14 at its lower end.

- 45 15 represents an oil-supply pipe connecting the cylinder 13 with a suitably-located supply-tank 16, said pipe having a stop-cock 17, by which the supply of oil may be regulated.

- 50 18 represents a glass gage in the supply-tank, by which the amount of oil contained therein may be readily noted.

- 55 19 represents a piston-rod working in the oil-cylinder 11. To the upper end of the piston-rod 19 is pivoted at its center an S-link 20. One of the ends of the S-link is loosely pivoted at 21 to an arm 22, said arm being in turn pivoted at 23 to a fixed point.

24 represents a lever pivoted to a fixed point, as shown at 25, said lever having one end of the S-link loosely pivoted thereto, as shown at 26.

27 represents holes in the lever 24 for adjustably securing the two ends of a cable 28. The cable 28 passes over a double-grooved pulley 29, said pulley being journaled on a bolt 30. The bolt 30 is secured at one of its ends to a block 31, said block being in turn secured to some stationary support. The bolt 30 is provided with a squared portion 32, which works in an elongated slot 33 in the block 31. By the means of the slot-and-bolt connection the pulley 29 may be shifted and regulated in a lateral direction.

34 represents a sleeve surrounding the bolt, and 35 washers on the same, which permit of a free movement of the pulley.

36 represents a nut on the end of the bolt for holding the pulley in place.

37 38 represent arms rigidly secured to the pulley 29, said arms extending out nearly on line with the side of the elevator.

39 40 represent pivoted points on the arms 37 38, said points being permitted to bend inward, as shown in Fig. III, but being prevented from bending outward by shoulders 41 42.

43 represents a projection on the elevator, said projection at proper times engaging the points 39 40 of the arms 37 38.

The cable 28 is provided with sleeves 44, 45 with which screw-threaded portions 46 of the same may engage, so that the cable may be regulated as to length.

46 represents a pipe leading from the oil-cylinder 11 to a cylinder 47, through which water and oil may be admitted to the main cylinder 10.

48 represents a piston-rod working in the cylinder 47, by which means the proper valves are operated by which water is admitted to the main cylinder and the elevator is operated.

49 represents an S-link of the same construction as the one heretofore described, said link being pivoted to the upper end of the piston-rod 48, and a lever 50, of the same description as the lever 24, pivoted to said link at 51 and to a fixed point 52. The lever 50 has a rope or cable 53 attached to both of its

ends, said cable passing around suitable pulleys 54 55, and passing through the elevator in order that the operator may work the piston-rod 48, and thus operate the elevator.

5 56 represents a set-screw which may be used, if desired, to limit the movement of the lever 24.

The operation is as follows: As the elevator ascends, the projection 43 will come in 10 contact with the point 39, and the arms 37 38 will be thrown into the position shown in dotted lines, Fig. I, thus rotating the pulley 29 to a certain extent, thus through the cable 28 throwing the lever 24 into the position 15 shown in dotted lines, Fig. I, which, by means of the S-link, depresses the piston-rod 19 and forces the oil in the oil-cylinder 11 through the pipe 46 into the cylinder 47, where at the proper time it enters with the water into the 20 cylinder 10 and lubricates the same. As the elevator descends, the projection 43 will strike the point 40 and the arms 37 38 will be thrown back to their original position, thus through the connections described raising the piston-rod 19 and permitting a fresh supply of oil 25 to enter the cylinder 11, ready to be forced out by the ascent of the elevator. The points 39 40 are beveled on the outside, and are constructed to bend inward, so that if the projection 43 should strike the same from the outside the points would give and no serious damage be done.

I have described my device in connection with a lubricator and hydraulic elevator; but 35 it will be seen that I can readily apply my link-motion to a steam-elevator and to various other devices too numerous to mention. The link construction forms a compact means for either transmitting motion to or from a piston-rod, the same permitting the piston-rod 40 to work always in the same plane, and thus avoid friction and wear.

The lever 24 may at times be used as shown 45 in Fig. II, as it may be desired at times to use a spring to force the piston in one direction instead of the cable 28.

I claim as my invention—

1. The combination of a piston-rod, S-link pivoted at its center to the piston-rod, one 50 end of said link being pivoted to a pivoted arm 22, and the other end of said link being

pivoted to a suitable operating device, substantially as described, and for the purpose set forth.

2. The combination of a piston-rod, S-link 55 pivoted at its center to the piston-rod, one end of said link being pivoted to an arm 22, and the other end of said link being pivoted to an operating-lever 24, substantially as described, and for the purpose set forth. 60

3. The combination of a piston-rod, S-link pivoted at its center to the piston-rod, one end of said link being pivoted to an arm 22, lever 24, pivoted to a fixed support and having the other end of the S-link pivoted there- 65 to, and means for operating the lever 24, substantially as described, and for the purpose set forth.

4. The combination of a piston-rod, S-link pivoted at its center to the piston-rod, piv- 70 oted arm 22, to which one end of the link is pivoted, lever 24, to which the other end of the link is pivoted, pulley 29, means for rotating said pulley, and a cable connecting said pulley with the lever 24, whereby said 75 lever is operated, substantially as described, and for the purpose set forth.

5. The combination of a piston-rod, S-link pivoted at its center to the piston-rod, arm 22, to which one end of the link is pivoted, lever 80 24, to which the other end of the link is pivoted, laterally-adjustable pulley 29, cable connecting the pulley with the lever 24, arms 37 38, secured to the pulley, elevator 1, and a projection on said elevator for engaging the 85 arms 37 38, and thus rotating the pulley 29, substantially as described, and for the purpose set forth.

6. The combination of the S-link 29, pivoted to a piston, lever 24, to which the link 90 is pivoted, said lever having holes 27, pulley 29, adjustable cable 28, connecting the pulley 29 with the lever 24 by means of the holes 27, arms 37 38 on the pulley, pivoted points 39 40 on the arms 37 38, elevator 1, and projection 43 on the elevator for engaging the points 39 40, substantially as described, and for the purpose set forth. 95
